VACUUM PRODUCTION APPARATUS

Kenneth C. D. Hickman, Rochester, N. Y., assignor, by mesne assignments, to Eastman Kodak Company, Rochester, N. Y., a corporation of New Jersey

Application June 14, 1945, Serial No. 599,381

6 Claims. (Cl. 230—101)

1

This invention relates to improvements in process and apparatus for producing rarefied atmospheres by means of ejector or condensation pumps.

Condensation and ejector pumps actuated by organic working fluids are well known in the art. It has also been known to utilize multistage ejector or condensation pumps actuated with organic working fluids and to fractionate the working fluid during operation and to deliver appropriate fractions to appropriate jets, i. e., high vapor pressure fractions are delivered to jets operating against the higher pressures, while low vapor pressure constituents are delivered to jets operating against low pressures.

This invention has for its object to provide improved ejector and condensation pumps of the foregoing type. Another object is to provide improved pumping procedure whereby a system can be evacuated with an organic working fluid issuing through an ejector or condensation pump nozzle. A still further object is to provide a multistage pump actuated with an organic vapor propellant which, during operation, will have high speed when large volumetric capacity is required and ability to reach low pressures when low volumetric capacity and low pressures are required. Another object is to provide a pump adapted to maintain appropriate levels of organic propellant fluid while pressures in the pump are subject to considerable variation. A still further object is to improve the state of the art. Other objects will appear hereinafter.

These and other objects are accomplished by my invention which includes producing a rarefied atmosphere with an organic vapor propellant pump by delivering organic propellant to the jet of the pump so that high vapor pressure components are used during the stage in the pumping operation when large volumetric capacity and moderate pressures are required and by delivering low vapor pressure propellant components during the stage when lower pressures and lower volumetric capacity are required.

In the following examples and description I have set forth several of the preferred embodiments of my invention but it is to be understood these are given by way of illustration and not in limitation thereof.

In the accompanying drawing I have illustrated in a single figure a vertical section of a multistage organic vapor propellant pump embodying the principles of my invention. Referring to the drawing, numerals 6, 8 and 10 designate a plurality of pumps connected in series by conduits

2

12 and 14, respectively. Pump 10 operates against the lowest pressure and produces the lowest pressure in its low pressure end 16, which is to be connected to the system to be evacuated (not shown). Pump 6 operates against the highest backing pressure and its high pressure end 18 is connected to a backing pump (not shown). Numerals 20, 22 and 26 designate boilers which supply actuating vapor to pumps 6, 8 and 10 respectively by way of conduits 28, 30, and 32. These conduits terminate in jet nozzles 34, 36 and 38. Pumps 6, 8 and 10 are provided with diffuser tubes 40, 42 and 48 respectively, which cooperate with the jet nozzles 34, 36 and 38, to form a pumping unit. Each of these diffusers is surrounded by a jacket through which cooling fluid is circulated.

Numeral 50 designates a conduit which serves to collect spent pumping fluid draining from the high pressure end of pumps 6, 8 and 10. This conduit is provided with U tubes 52 and 54 which, during operation, are filled with liquid and thus prevent passage of gas from the high pressure end of one pump into the high pressure end of the other. Conduit 50 drains into a reservoir 51 containing pump fluid 53 which is connected by conduit 56 to circulating pump 58. Conduit 60 leads from the outlet of pump 58 to boiler 20, provided with a plurality of baffles 62. A U tube 64 connects boiler 20 with boiler 22, which is also provided with a plurality of baffles 66. U tube 68 connects boiler 22 with boiler 26, also provided with baffles 70. Numeral 72 indicates a conduit through which liquid overflowing from boiler 26 flows into reservoir 51. Numerals 74, 76 and 78 designate heaters for boilers 20, 22 and 26, respectively.

Numerals 80 designates an electric motor which drives pump 58, the source of electric energy being designated at 82. One terminal of the source of electric power leads to a manometer device 84 filled with an electrical conducting liquid, such as mercury. One end of the manometer is connected to the high pressure end of pump 6 by conduit 86. Numerals 88, 90 and 92 designate electric leads which terminate inside manometer 84 and make electrical contact with the mercury therein, depending on its height, and which lead to an electric resistor 94, one end of which leads to motor 80 and delivers current thereto in cooperation with the other lead wire 96. This arrangement constitutes a monitoring device automatically supplying pump fluid according to variations in pressure in the pump.

In operating the apparatus illustrated in the drawing a suitable pump fluid, such as a fraction

of a petroleum oil, such as described in Hickman Patent 2,379,436, dated July 3, 1945, or a synthetic fluid, such as di-amyl phthalate, di-octyl phthalate, or mixtures thereof, is introduced into the boilers 20, 22 and 26 and reservoir 51. The backing pump connected to conduit 18 is actuated and conduit 16 is connected to the system to be evacuated. Pump 58 is then actuated by current supplied to leads 82. Heating units 14, 76 and 18 are put into operation. Vapors from boiler 20 pass through conduit 28 and issue as a pump stream through nozzle 34. The vapors entrain gases from conduit 12 and force them into the opposite and high pressure end of pump 6. The spent pump fluid is condensed on the cool walls of diffuser 40 and flows by gravity into U tube 52 and thence into conduit 50. Gases from the high pressure end of pump 6 are removed by the backing pump connected to conduit 18. The same action takes place in connection with pump 8, vapors from boiler 22 passing through jet nozzle 36 and forcing vapors from conduit 14 into conduit 12. Spent condensed pump fluid flows through U tube 54 into conduit 50. Similarly vapors from boiler 26 pass through nozzle 38 of pump 10, forcing gases from 16 into conduit 14. Spent pump fluid flows into conduit 50 and thence into reservoir 51. The liquid in reservoir 51 is then withdrawn by pump 58 and returned to boiler 20. Any over-supply of liquid thus returned or unvaporized overflows into U tube 64 and flows thence into boiler 22. Liquid unvaporized in boiler 22 overflows into U tube 68 and flows into boiler 26. Excess liquid is then returned to reservoir 51 through conduit 72.

Manometer 84 is adjusted so that when high pressures exist in pump 6 the column of mercury makes contact with lead wire 88 and then supplies the full current to motor 80. Pump 58 is, therefore, run at high speed and supplies a large volume of pump fluid to boiler 20 when high pressures exist in pump 6. On the other hand, when low pressures exist in pump 6 the column of mercury falls and makes contact only with lead wire 92, which necessitates passage of the electric current through the entire resistor 94. This cuts down the speed of motor 80 and consequently the speed of pump 58 so that low volumes of pump fluid are delivered to boiler 20 when the pressure in pump 6 is low. The pressures in pumps 6, 8 and 10 vary together so that the conditions of supply of pump fluid to pumps 8 and 10 are the same as for pump 6. Intermediate lead 90 gives an intermediate speed to motor 80 and pump 58 when the pressure in pump 6 is intermediate. It will be appreciated that there is fractionation of the pump fluid in each of the boilers 20, 22 and 26. This fractionation is particularly effective when low volumes of liquid are supplied. The baffles 62, 66 and 70 somewhat slow the passage of the pump fluid in the boilers and increase the fractionating effect.

While I have illustrated heating the boilers with an electric resistor, other methods of heating such as, for instance, steam may be used. The boilers may be all heated to the same temperature or graduated heat may be employed. A constant heat input is preferred, i. e., one using a constant B. t. u. input (electric or gas heat) with variable temperature or a constant temperature input (such as steam heat) with a variable B. t. u. supply.

Let it be supposed that all of the boilers 20, 22 and 26 are surrounded by steam jackets heated by steam at 180° C. and that a mixed organic liquid

is furnished by the reservoir 51 such that a pressure of $\frac{1}{2}$ an atmosphere is produced in boiler 20 during the first few minutes of operation. As vaporization of the pump fluid takes place, the lighter constituents will be distilled out and will pass through jet nozzle 34 and the pressure in boiler 20 would, therefore, fall. If, however, pump fluid is supplied to the boiler at such a rate as to supply the volatile constituents as fast as they are evaporated, the pressure in boiler 20 will remain fixed at about $\frac{1}{2}$ an atmosphere. This condition implies that a quantity of pump fluid freed of these more volatile constituents will overflow through 64 into the boiler 22. Here evaporation continues but, since the volatiles have been removed and the temperature is substantially the same as the boiler 20, the pressure of vapors in the boiler 22 will be less at say $\frac{1}{10}$ of an atmosphere. The process continuing, the residue from boiler 22 will pass through 68 into boiler 26 which, in turn, will discharge the final pump fluid residue through conduit 12 into reservoir 51. The pressure in boiler 26 may be only a few inches by oil manometer.

The state of affairs just described is for normal operation. However, suppose that there is a heavy load on the system in the starting period. This will be reflected quite exactly in increased forepressure in pump 6. This will increase the height of the mercury in manometer 84 and will increase the speed of pump 58, with the result that more volatile oil will enter boiler 20 and considerably more volatile fractions will overflow into boilers 22 and 26. This will raise the pressure in all the boilers and will result in increased volumetric pumping capacity at the expense of ultimate vacuum. However, ultimate vacuum is not now important, since the system is overloaded and throughput alone is of importance.

Consider the opposite case. The system to be evacuated has steadied down, i. e., the volume of gases to be removed is lower, the vacuum is improving and the forepressure in 18 falls to an abnormally low value. The manometer control then shifts to lower the speed of pump 58, which lowers the speed of delivery of pump fluid to the boilers 20, 22 and 26. The more volatile constituents are more or less completely removed in boiler 20 so that only intermediate constituents flow into boiler 22 and only the lowest vapor pressure constituents into boiler 26. The operating pressure, therefore, falls in all of the boilers but the average boiling point of the operating fluid in each of the boilers rises and, therefore, the ultimate vacuum of the system improves and there is a large increase in degree of evacuation, as well as pumping speed at the low pressure.

What I claim is:

1. A fractionating multistage organic vapor propellant pump which comprises a plurality of vapor condensation pumps, a plurality of interconnected boiler compartments to each of which is connected one of said vapor condensation pumps, heating means for each boiler compartment, a circulatory passage for pump fluid through said boiler compartments, means for conveying condensed pump fluid from each vapor condensation pump to said circulatory passage, and a controllable pump means in said circulatory passage for regulating the rate of flow of pump fluid through said boiler compartments whereby the degree of fractionation of pump fluid may be controlled.

2. A fractionating multistage organic vapor propellant pump which comprises a plurality of

vapor condensation pumps, a plurality of boiler compartments to each of which is connected one of said vapor condensation pumps, heating means for each boiler compartment, a circulatory passage for pump fluid through said boiler compartments, a pump fluid comprised of constituents boiling at different temperatures, conduit means for returning condensed pump fluid from each vapor condensation pump to said circulatory passage, and means for regulating the rate of flow of said pump fluid through said boiler compartments whereby the degree of fractionation of said pump fluid in said boiler compartments may be controlled.

3. Vacuum pumping apparatus comprising in combination liquid-channeling means, circulating means associated with said channeling means for circulating pumping fluid through said channeling means, heating means along said channeling means for producing vapors of pumping fluid at a plurality of zones along said channeling means, vapor condensation pumping means communicating with said channeling means at said zones, means connecting said pumping means with said channeling means for returning condensed pumping fluid from said pumping means to said channeling means, and pressure-responsive controlling means communicating with said pumping means and connected with said circulating means for varying the circulatory rate of said circulating means in response to variations in pressure in said apparatus.

4. Vacuum pumping apparatus comprising in combination liquid-channeling means, circulating means associated with said channeling means for maintaining in continuous circulation through said channeling means a stream of organic liquid comprising constituents boiling at different temperatures, a plurality of heating means at spaced apart zones along said channeling means for producing in said zones vapors of different compositions, vapor condensation pumping means communicating with said channeling means at each of said zones, condensing means for said pumping means, means for returning condensate from said condensing means to said chan-

neling means at the first of said zones along said channeling means, and pressure-responsive controlling means associated with said circulating means for controlling the rate of circulation of liquid through said channeling means, said controlling means being effective to accelerate said rate of circulation with increases in pressure in said apparatus and to decelerate said rate of circulation as said pressure decreases.

- 10 5. A fractionating multistage organic vapor propellant pump which is adapted to fractionate the organic working fluid and deliver fractionated components to appropriate stages of the pump, which pump comprises in combination a plurality of boiler compartments, a plurality of jets, means connecting each said boiler compartment with at least one of said jets for delivering vapors from said compartments to said jets, means for supplying pumping fluid to said boiler compartments, and means for varying the composition of pump fluid supplied to each said boiler compartment so that components of relatively high vapor pressure are vaporized during that part of the pumping operation when large volumetric capacity and moderate pressures are required and so that components of relatively low vapor pressure are vaporized during that part of the pumping operation when lower pressures and lower volumetric capacity are required.
- 15 20 25 30 35 6. Apparatus as defined in claim 5 wherein said means for varying the composition of pump fluid comprises a monitoring device actuated by variations in pressure in the pump for automatically varying the composition of pump fluid supplied to the pump.
